UNITED STATES PATENT OFFICE

132,318

DESIGN FOR A COUNTER DISPLAY CASE

Thomas A. Schutz, Chicago, Ill., assignor to Parke, Davis & Company, Detroit, Mich., a corporation of Michigan

Application January 19, 1942, Serial No. 105,298

Term of patent 3½ years

To all whom it may concern:

Be it known that I, Thomas A. Schutz, a citizen of the United States, residing at Chicago, Cook County, Illinois, have invented a new, original, and ornamental Design for Counter Display Cases, of which the following is a specification, reference being had to the accompanying drawing, forming a part thereof, and in which:

Fig. 1 is a top plan view of a counter display case, showing my new design;

Fig. 2 is a front elevational view; and

Fig. 3 is a side elevational view thereof.

Fig. 4 is a sectional view taken substantially on line 4—4 of Fig. 2 and in the direction of the arrows; and

Fig. 5 is a sectional view taken substantially on line 5—5 of Fig. 2 and in the direction of the arrows.

I claim:

The ornamental design for a counter display case, as shown.

THOS. A. SCHUTZ.
